COMBINED COUNTER DISPLAY AND INSPECTOR FOR AIR FILTER CARTRIDGES

Donald L. Paster, Riverside, R.I., assignor to Fram Corporation, Providence, R.I., a corporation of Rhode Island

Application May 1, 1958, Serial No. 50,698

Term of patent 7 years

(CL. D80—9)

FIG. 1

FIG. 2

FIG. 3

Fig. 1 is a perspective view of a combined counter display and inspector for air filter cartridges embodying my new design;

Fig. 2 is a front elevational view thereof in an open position, with an air filter cartridge indicated in broken lines for purposes of illustration only; and

Fig. 3 is a perspective view thereof as shown in Fig. 2.
I claim:

The ornamental design for a combined counter display and inspector for air filter cartridges, substantially as shown and described.
